UPHOLSTERY FABRIC.

No. 15,413.

Patented Sept. 16, 1884.

UNITED STATES PATENT OFFICE.

DAVID B. KERR, OF PHILADELPHIA, PENNSYLVANIA, ASSIGNOR TO HOYLE,
HARRISON & KAYE, OF SAME PLACE.

DESIGN FOR AN UPHOLSTERY FABRIC.

SPECIFICATION forming part of Design No. 15,413, dated September 16, 1884.

Application filed August 2, 1884. Term of patent 7½ years.

To all whom it may concern:

Be it known that I, DAVID B. KERR, a citizen of the United States, residing at Philadelphia, in the county of Philadelphia and State 5 of Pennsylvania, have invented and produced a new and original Design for an Upholstery or Curtain Fabric, in such shades as may be desired.

Said design or pattern for a curtain consists 10 of the dado A, formed to represent winged animals, scrolls, and other ornamental figures, the ornamental guards B, borders C, representing winged animals, scrolls, and other figures, and a body, D, for the curtain, representing 15 winged animals and other ornamental figures, as is illustrated by the photographic print ac-

companying this specification, which conveys to any one skilled in the art of weaving a clear understanding of the same, and is sufficient to enable such persons to use my invention. 20

The design may be woven in tapestry or damask.

What I claim as my invention, and desire to secure by Letters Patent, is—

The design for a tapestry or damask curtain 25 fabric, as shown in the photographic print accompanying this specification.
